UNITED STATES PATENT OFFICE.

GEORGE L. WEBB, OF SPENCER, NORTH CAROLINA.

ADJUSTABLE JOURNAL WEDGE.

Application filed May 14, 1926. Serial No. 109,134.

This invention relates to an adjustable cap or wedge plate for the journals of railway cars and the like.

It is well known to those skilled in the art that the journal boxes used in the construction of railway cars are cast and, consequently, it frequently occurs that these boxes vary slightly in transverse area and in the positions of the side lugs provided for the attaching bolts. As a result of these slight differences it has been found that when the brasses are positioned in the housings and upon the journals one axle of a truck is not exactly parallel with the other axle or axles but is sometimes as much as three-eighths of an inch out of proper position at one end. If the axles are not exactly parallel the wheels supporting the axle which is not properly positioned will be maintained at an acute angle relative to the sides of the supporting rails during the forward movement of the truck and, as a result, the flange of one of the wheels will receive twice the wear to which it would ordinarily be subjected and, consequently, considerable expense is entailed in redressing or turning the wheels and ultimately replacing them.

It is an object of the present invention to provide a means whereby any variations in the relative positions of a pair of journal boxes can be compensated for very readily so that the axle projecting into these boxes will be maintained parallel with the other axle or axles even though the boxes may not be accurately aligned.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a horizontal section through a journal box showing the parts therein in plan.

Figure 2 is a vertical section through the journal box showing the parts therein in elevation.

Figure 3 is a section on line 3—3, Figure 1.

Figure 4 is a plan view of the brass constituting a part of the bearing.

Figure 5 is an elevation of a shim constituting a part of the present invention.

Referring to the figures by characters of reference 1 designates a journal box of the usual construction provided at the sides with ears 2 for the reception of bolts or the like employed for fastening the journal box to the truck. Formed upon the inner surfaces of the sides of this journal box are bearing lugs 3. A portion of an axle has been indicated at 4 and the end portion thereof supports a brass 5 the side portions of which converge upwardly as at 6. Lugs 7 are extended laterally from the brass and project into engagement with the outer sides of the lugs 3. A cap or wedge plate 8 is mounted on the brass 5 and has a recess 9 in its lower face the sides of which diverge downwardly. This recess is adapted to receive the upper portion of the brass 5. Ordinarily the cap or wedge plate 8, formed in one piece, is adapted to abut against and be guided by the lugs 3 but obviously where the boxes are not properly aligned, such an arrangement prevents the axle from being disposed parallel with the other axle or axles of the same truck.

For the purpose of allowing adjustment of the brass and proper positioning of the axle, a wear plate 10 is connected to each side of the cap or wedge plate 8 by means of screws 11 entering the sides of the cap or wedge plate. These wear plates 10 may be positioned normally within recesses 13 formed in the sides of the cap or wedge plate 8. Where the lugs 3 are spaced apart excessive distances, however, as shown for example in Figures 1 and 3, shims 14 can be positioned between the wear plates and the sides of the cap or wedge plate 8, each of these shims being formed with slots 15 so that the stem can be inserted downwardly between the wear plates and the cap or wedge plate 8 and straddle the screws 11. After the shims have thus been positioned the screws are tightened and if the shims are of the proper thickness the wear plates will thus be held close to the lugs 3. Under some circumstances it is necessary, in order to hold the axle parallel with the other axle or axles of the truck to remove the shim 14 from back of one of the wear plates and, under other conditions, it is advisable to have two shims back of one wear plate and no

shim back of the other. Obviously various other arrangements can be provided for the purpose of shifting the center of the brass 5 relative to the center of the box 1, thereby 5 to compensate for any variation in alinement of the two boxes into which the ends of the axle 4 project.

It will be apparent that when the journal boxes of a truck are equipped with means 10 such as herein described, it becomes possible readily to properly position the axles so that they will be parallel during the movement of the truck and the drag upon one or more of the supporting wheels resulting from non-alinement of journal boxes will be entirely 15 eliminated. Thus wear upon the wheels will be greatly reduced and the cost of maintenance correspondingly lessened.

What is claimed is:

20 1. The combination with a journal box of a railway car having opposed bearing lugs therein, of a brass centering member interposed between the lugs and means carried by the respective side portions of said member for holding the member at predetermined distances from the respective lugs.

25 2. The combination with a journal box of a railway car having opposed guide lugs therein, of a brass centering member extending 30 between the lugs, a wear plate connected to one side of said member, and spacing means interposed between the member and the wear plate, said wear plate being positioned for sliding engagement with one of 35 the lugs.

30 3. The combination with a journal box of a railway car having opposed bearing lugs therein, of a brass centering member mounted for movement between the lugs, a wear

plate detachably and adjustably connected to one side of said member for sliding engagement with the adjacent lug, and a shim insertable between said plate and member. 40

4. The combination with a journal box of a railway car having opposed bearing lugs 45 therein, of a brass centering member extending between the lugs, wear plates detachably and adjustably connected to the sides thereof for sliding engagement with the lugs, and means insertable between said member and one of the wear plates for holding the member against lateral shifting relative to the journal box after adjustment of said member to a predetermined position within 50 the box. 55

5. The combination with a journal box of a railway car having opposed bearing lugs therein, of a brass centering member between the lugs movable laterally to a predetermined position relative to the lugs, and means carried by said member for holding it properly spaced from the lugs subsequent to said 60 adjustment. 60

6. The combination with a journal box of a railway car having opposed bearing lugs therein, of a brass centering member between the lugs movable laterally to a predetermined position relative to the lugs, and means carried by said member for holding it properly spaced from the lugs subsequent to said 70 adjustment, said means including wear plates adjustably and detachably connected to the member and spacing means for cooperating with said member and the wear plates. 75

In testimony that I claim the foregoing as my own, I have hereto affixed my signature.

GEORGE L. WEBB.
